ROLL SCOURING BLOCK

Application filed October 7, 1929. Serial No. 398,046.

The present invention relates to roll scouring blocks for use in keeping rolls (such as are used in the manufacture of sheet metal) in proper condition. While external cylindrical surfaces are mentioned particularly here as the subject of operation, modifications of my design may be used in finishing internal cylindrical surfaces such as engine cylinders, pump cylinders, and the like.

10 The usual type of scouring block is in the form of a brick or block made of artificially bonded abrasive material. In using a scouring block it is mounted on a plank about 8 feet long at a distance of about 1 foot from 15 the end of the plank. The plank is slidably and rotatably mounted on a rod which is supported a short distance above the surface of a roll, the rod lying parallel to the axis of the roll to be scoured. The block is on the 20 under side of the plank and is pressed against the roll by a workman who puts his weight on the end of the plank remote from the pivot. If the weight of the workman be 150 pounds 25 the force on the abrasive surface of the block is about 1200 pounds in the example we have given. When the particular portion of the wheel on which the block has been bearing is sufficiently scoured the plank and block are moved along in a direction parallel to the axis 30 of the roll and a new portion of the roll is scoured. In the manufacture of sheet metal it is quite common to roll the sheets at such a high temperature that the rolls may be red hot.

35 Certain difficulties arise in the use of abrasive blocks in the manner described. They are for example subject to breakage so that they have to be changed frequently in general, causing loss of time as well as the replacement of expensive abrasive blocks. This breakage is due partly to the severe mechanical strains produced by the high pressures which are applied to the blocks in conjunction 40 with the high temperatures at which they are used, the high temperatures being produced by conduction from the hot rolls and by the friction experienced in scouring the rolls.

45 I use the following means to reduce the difficulties referred to above. My abrasive

block is illustrated in the accompanying drawing in which:

Figure 1 gives a perspective view of one of my fluted roll blocks; and

Figure 2 represents diagrammatically the 55 mode of application of one of my blocks to a roll.

Referring to the drawing in detail, 2 represents a roll block and 3 represents a diagonal slot whose plane makes an acute angle 60 with the long edge 4 of the base of the block.

The blocks are made of a mixture of abrasive grains (of silicon carbide for example) and ceramic bonding material. This mixture is molded to a form similar to that shown in Fig. 1. The diagonal slots are made in the fresh molded material with a saw blade or disk wheel. The width 5 of the gap made

is thus small as compared with its depth below the abrasive surface 6 of the block. The 65 depth of the slots should not be greater than about half the depth of the block. A certain amount of clearance is thus provided which clearance tends to prevent clogging of the abrasive surface with débris from the roll. The slots however also relieve the strains due to differences in temperature between the hot abrading surface portions of the block and the cooler portions of the block which lie adjacent to its support on its mounting. As 70 has been pointed out these temperature differences may be very large owing to conduction from the hot rolls and the large amount of work performed against large frictional forces.

On the other hand the projecting portions 7 which lie between the slots are left sufficiently massive to render them very resistant to mechanical forces tending to break them off. This resistance of the projections 7 is increased by the diagonal direction of 75 the slots which leads to the distribution of severe mechanical stress among the projections to a greater extent than would be the case if the slots 3 were perpendicular to the long edge 4 and therefore parallel to the direction of the frictional forces developed in securing the rolls.

The resistance of the projections to stresses produced by differences of expansion and 80 produced by the large frictional forces devel-

oped depends on the particular bond used to hold the abrasive grains. I may use therefore bonds which I have found to give the best resistance to mechanical stresses at the temperatures experienced in roll scouring.

While the application of fluted scouring blocks has been particularly described with reference to roll scouring I do not wish to limit the use of blocks of the design shown to such use. Such blocks may be used in other ways within the spirit of the following claims.

I claim:

- 15 1. A scouring block having a plurality of slots arranged diagonally to the long axis of the block, said slots being narrow as compared with their depth and extending below the abrasive surface to not more than half the depth of the block.
- 20 2. The method of reducing stresses in securing blocks subjected to high temperature contacts which consists in providing the abrasive surface with slots which are narrow as compared with their depth and which are arranged diagonally to the direction of the frictional forces during operation.
- 25 3. A scouring block composed mainly of an abrasive material having a high thermal conductivity and having a series of narrow slits arranged transversely to the greatest dimension of the abrasive surface and extending into the abrasive body a distance greater than the width of the slit whereby temperature stresses in the abrasive are substantially prevented.

In testimony whereof I affix my signature.
FRANK L. BUELL.
